UNITED STATES PATENT OFFICE.

GEORGE A. LAW, OF MECHANICSVILLE, NEW YORK, ASSIGNOR OF ONE-HALF TO
THOMAS F. HICKEY, OF MECHANICSVILLE, NEW YORK.

AUTOMATIC LOCK FOR SWITCH-STANDS.

1,358,376.

Specification of Letters Patent.

Patented Nov. 9, 1920.

Application filed May 21, 1919. Serial No. 298,732.

To all whom it may concern:

Be it known that I, GEORGE A. LAW, a citizen of the United States, residing at Mechanicville, in the county of Saratoga and 5 State of New York, have invented certain new and useful Improvements in Automatic Locks for Switch-Stands, of which the following is a specification.

This invention relates to automatic locks 10 for switch stands and has for its object the provision of improvements whereby the key must be allowed to remain in the lock if the stand is to be operated, and when the key is removed, the lock will automatically close; 15 further, to provide a novel lock, particularly adapted for use in connection with switch stands but which may have a more general application; still further, to provide an automatic lock for switch stands having 20 a novel controlling guard with which the key coöperates, said guard preventing the lock from being opened, and preventing the switch stand from being rendered operative unless the proper key is used.

25 My improved controlling guard constitutes an important element of the invention. This guard is in the form of a removable part which can be interchanged with other guards of different formation whenever it 30 is desired that another style or kind of key be used; furthermore, the improved guard permits the automatic lock to be used in connection with any key used by the particular railroad on which the switch stand is provided. 35 As the principal railroads have different keys for their switch stands and the keys for the switch stands of one railroad will not serve to open the locks of the switch stands of another railroad, my invention 40 provides for its adaptability to use on any switch stand by the provision of a controlling guard adapted to the form of key used on the particular railroad, thereby enabling the lock to be made in standard form, adaptable 45 for use on any railroad with provision for the application of a controlling guard of the particular kind required for the keys used on the railroad in question. This feature has great practical advantages because 50 the standard type of switch stand is now in use on the principal railroad systems. My improvements may be applied to the lever of any standard switch stand, or, may be

embodied in the lever and the latter substituted for the ordinary type of locking lever 55 and a controlling guard used according to the key employed for the switch stands of the railroad in question.

I am aware that my improved lock is adapted for other uses than on switch 60 stands. Modifications may be resorted to if the essential principles of the invention are retained, and the disclosure of the invention is to be considered as illustrative, rather than restrictive, of the scope thereof. 65

In the accompanying drawings,

Figure 1 is a side elevation of a switch stand provided with my invention, in locked condition;

Fig. 2 a similar view, the top of the lock 70 casing having been removed and the key being shown in position, ready to be operated to unlock the stand;

Fig. 3 a detail view of the lock with its cover removed, the key being shown in unlocking position and the parts unlocked; 75

Fig. 4 a longitudinal section on the line 4—4, Fig. 2, showing the key in position where it must remain while the stand is being operated; 80

Fig. 5 a cross section on the line 5—5 of Fig. 1; and

Fig. 6 a detail view of the cover or face plate of the lock.

The column of the stand appears at 1, the 85 stem which controls the switch is shown at 2, the lever appears at 3, the slideable polygonal locking member is designated 4 and adapted to enter the polygonal socket 5 in the column 1; links 6 connect the locking 90 member 4 to the lever 3. The locking member 4 has an ear or tongue 7 provided with an opening 8.

My improved lock may form a part of the 95 lever 3 when the latter is manufactured, or, it may be applied to any standard lever, such as used on switch stands of the type shown. The lever carries a casing 9 provided with an opening 10 through which the ear or tongue 7 is adapted to pass 100 through the interior of the casing 9. The casing 9 has a top or cover 11 which may be suitably secured as, for instance, by rivets or other fastening which cannot be readily removed. The cover 11 is provided with a 105 hollow projection 12 to receive the end of

the tongue or ear 7 when the parts are locked.

Secured to the casing 9 are cross pieces 13 and 14 which may be fastened by any suitable devices 15, in each instance. The hook shaped latches 16 which are adapted to enter the eye 8, have their tails pivoted to the parts 15 of the cross piece 14 and are free to swing between the cross piece 14 and the casing 9 but are normally pressed toward locking position by springs 17 contained within the casing and having their ends anchored in slots in the cross piece 13 as shown at 18.

15 Slidable through the cross piece 13 and guided thereby so that it can only move in a straight path, is the operating member 19 which has forks 20 adapted to bear on the tails of the hook shaped latches 16. The 20 lower end of the operating member 19 is provided with converging arms 21. Shoulders 22 prevent the member 19 from dropping past the position shown in Fig. 2. Filler blocks 23 may be provided. When 25 the operating member 19 is moved upwardly from the position shown in Fig. 2 to that shown in Fig. 3, the forks 20 by their engagement with the tails of the hook shaped latches 16 retract the heads of the latches 30 from locking position and release the tongue 7.

An improved controlling guard 24 is pivoted at 25 to the casing 9 and provided with a notch 26 and a wing 27 having a curved 35 surface 28. The wing 27 overlies the lower end of the operating member 19 and is relatively thin. One of the arms 21 is adapted to enter the notch 26 and thereby the member 19 is normally locked as shown in Fig. 2.

40 A stud or pintle 29 is adapted to receive the key 30 which is used for operating the lock. If the key 30 be turned to engage the arm 21 which enters the notch 26, the member 19 cannot be unlocked and shifted because the controlling guard 24 prevents any shifting of the actuating member 19, except when the guard is released. Consequently, the lock cannot be forced by an ordinary key in the manner specified. On the other 45 hand, unless the key used has a bit 31 which is of such length and thickness as to be adapted to engage the curved edge 28 of the guard 24, the guard 24 cannot be swung to release the notch 26 from the arm 21. 50 Furthermore, if the bit 31 is not so formed as to width and length that it will also engage the left hand arm 21, after it has released the guard 24, the member 19 cannot be shifted to release the hook shaped 55 notches 16. Now, according to requirements, whether by way of changing the lock after it has once been installed, or, adapting it to the keys used on the particular railroad on which the stand is provided, the guard 24

will be of such a form that there will be the 65 requisite distance between the curved edge 28 and the pintle 29, and the proper thickness of the wing 27, to be adapted for engagement by the bit 31 of the key intended for use. Consequently, by providing a 70 guard 24 whose wing 27 is provided with a curved edge 28 of proper form, my lock can be used on any switch stand to meet the requirements of the keys used by the railroad in question. This obviates the 75 necessity of making a special lock for each railroad system and enables the lock to be applied to the lever of any switch stand, all that is necessary being to provide a guard 24 adapted to the particular key which is 80 to be used.

When the key is out of the lock, the member 19 is in the position shown in Fig. 2 and is held by the notch 26, the hook shaped latches 16 being then in position to lock the 85 tongue 7. If the eye 8 is in alignment with the hooks of the member 16, locking will be effected but, if the lever 3 is in raised position and the parts are in locking condition, merely pressing down on the lever 3 or 90 allowing it to drop will cause the latches 16 to snap past the beveled end of the ear or tongue 7 and then to enter the eye 8. However, turning of the switch can only be accomplished when the key 30 is in the position shown in Fig. 3, that is, turned with the bit 31 engaged with the actuating member 19 to thereby hold the hook shaped latches 16 in retracted position. While the key is in the lock, the lever 3 can be raised 95 and turned to rotate the stem 2 and shift the switch. When the lever 3 is pressed down, or allowed to fall to, the position shown in Fig. 1, the entry of the member 4 in the socket 5 locks the switch in that position. On withdrawing the key 30 the lever 100 is then automatically locked. If the key 30 has been removed before the lever 3 is pressed downwardly, or allowed to drop, locking is automatically effected by the 110 latches 16 snapping past the end of the ear or tongue 7 and into the opening 8.

A suitable guard 32 (Figs. 1, 4, 6) may be provided for the key hole to keep out rain and sleet.

What I claim is:

In an automatic lock for a switch stand, the combination with an operating lever, of a lock carried by the lever provided with a pair of pivoted hook shaped locking 120 latches, a slidable operating member having a fork adapted to engage the tails of said locking latches and also having oppositely extending, angularly arranged arms, said arms being positioned to be directly engaged by the proper key used for operating the lock, a pivoted controlling locking guard adapted to engage one of the arms to hold 125

the operating member in locked condition, said controlling guard being provided with a free wing arranged alongside the oppositely extending arms and having an edge 5 positioned to be engaged by the proper key prior to engagement of the key with the arms and also when the arms are engaged

by the key, and an ear or tongue on the stand adapted to be engaged by the hook shaped latches. 10

In testimony whereof I affix my signature.

GEORGE A. LAW.
